UNITED STATES PATENT OFFICE.

DEWEY COFFIN, OF SAN FRANCISCO, CALIFORNIA.

ROAD SIGN.

Application filed September 10, 1925. Serial No. 55,525.

My invention to a new article of manufacture comprising a road sign construction wherein a tubular post flattened and split at its upper end into diverging upwardly 5 facing channels operates in conjunction with a sheet metal sign to form a substantial road sign.

The primary object of the present invention is to provide a new and improved construction for a road sign.

Another object of the present invention is to provide a new and improved article of manufacture.

A further object is to provide a new and improved construction for a road sign which shall be simple and economical and of a maximum efficiency.

A further object is to provide a new and improved article of manufacture comprising 20 a road sign of a particular structure wherein improved and simplified means are provided for rigidly engaging and supporting a sheet metal sign in such a manner that the same may be changed or renewed.

25 I accomplish these and other objects by means of the structure disclosed in the drawings forming a part of the present specification wherein like characters of reference are used to designate similar parts throughout 30 the said specification and drawings, and in which—

Fig. 1 is a broken front elevation of my improved road sign;

Fig. 2 is a side edge view thereof; and

35 Fig. 3 is a broken elevation of a modified form of the invention.

Referring to the drawings the numeral 1 is used to designate in general a tubular post flattened at the top or upper end thereof 40 and then split centrally and longitudinally to form lateral or diverging arms comprising upwardly facing channels 3.

The channels 3 are provided with apertures adjacent their outer ends to receive 45 detachable securing elements, such as a bolt 4 or the like, the purpose of which will hereinafter be more fully set forth.

In the preferred form of the structure the channel arms 3 are arranged or diverged 50 substantially at right angles to each other in order to engage adjacent lower edges of a substantially square sheet metal sign 6, as disclosed in Figs. 1 and 2 of the drawings.

The sheet metal sign 6 is provided with 55 apertures which register with the apertures in the channels or arms 3 through which

bolts 4, or other suitable detachable securing means, may be inserted to retain the lower edge or edges of the sign 6 securely in engaging relation with the channels 3. 60

By means of this novel arrangement and structure the channel arms 3 are integral extensions or arms which embrace the sheet metal sign along two adjacent edges thereof, and by reason of the diverging nature of 65 said arms or channels 3 an additional and rigid support is given to the sheet metal sign 6 which will tend to prevent bending thereof throughout the greater portion of its body, and in a manner which will not detract from the neat and ornamental appearance 70 of the entire road sign.

I prefer to use bolts or other suitable detachable securing means rather than rivets to rigidly secure the sheet metal sign 6 in 75 engaging relation with the channels 3 in order that the sign may be changed with the use of proper tools and a different sign of the same shape may be easily and readily installed in place of the old sign. 80

In Fig. 3 of the drawings I have illustrated a modified form of the invention wherein the channels or arms 3 are extended in alignment in opposite directions thereby forming a channel arranged to engage the 85 lower horizontal edge of a rectangular sheet metal sign 6' in much the same manner as hereinbefore described.

Having thus described my invention what I claim as new and desire to secure by Letters Patent is—

1. In an article of manufacture, a road sign comprising a tubular post flattened and split at its upper end to form arms, said arms being spread apart at substantially right 95 angles to form channels arranged to engage the edges of a rectangular sheet metal sign; and a sheet metal sign mounted with one corner thereof engaged within said channels.

2. In an article of manufacture, a road sign comprising a tubular post flattened and split at its upper end to form arms, said arms being spread apart to form diverging upwardly faced channels arranged to engage a corner of a sheet metal sign; and a sheet metal sign mounted with a corner thereof engaged within said channels; and securing means for retaining engaging relation between said channels and sign. 105

3. In an article of manufacture, a road sign comprising a tubular post flattened and split at its upper end to form arms, said arms 110

being spread to form upwardly facing and diverging channels arranged at substantially right angles to each other, and provided with lateral apertures adjacent the ends of said channels; a sheet metal sign having adjacent lower edges seated within the diverging channels of said post and provided with apertures registering with the apertures in

the channels; and detachable securing means passing through the registering apertures to 10 secure said sheet metal sign within said channels.

In witness whereof I hereunto set my signature.

DEWEY COFFIN.
